(57) **CLAIM**

The ornamental design for a mini projector, as shown and described.

DESCRIPTION

FIG. 1.1 is a front view of a mini projector showing the new design;

FIG. 1.2 is a rear view thereof;

FIG. 1.3 is a left-side view thereof;

FIG. 1.4 is a right-side view thereof;

FIG. 1.5 is a top view thereof;

FIG. 1.6 is a bottom view thereof;

FIG. 1.7 is a perspective view thereof;

FIG. 1.8 is an enlarged view of the lens portion of the design shown in FIG. 1.1.

FIG. 1.9 is an enlarged view of the lens portion of the design shown in FIG. 1.7.

(Continued)

The broken lines shown in the drawings form no part of the claimed design.
